CLAIM

The ornamental design for a capacitive electronic sensor head, as shown and described.

DESCRIPTION

FIG. 1 is a perspective view of the capacitive electronic sensor head of this invention;
FIG. 2 is a front view thereof;
FIG. 3 is a back view thereof;
FIG. 4 is a left side view thereof, the right side view being a mirror-image of the left side view;
FIG. 5 is a top view thereof; and,
FIG. 6 is a bottom view thereof.
